ROTARY COMPRESSOR FOR REFRIGERATING APPARATUS

Harry B. Hull and Alex A. McCormack, Dayton, Ohio, assignors to General Motors Corporation, Dayton, Ohio, a corporation of Delaware

Application November 6, 1937, Serial No. 173,222

2 Claims. (Cl. 230—147)

This invention relates to refrigerating apparatus and more particularly to rotary compressors for refrigerating systems and motor-compressing purposes.

5 While the advantages of rotary compressors have long been recognized, there has always been considerable difficulty in preventing leakage in rotary compressors where relatively high pressure differences are encountered. This is because of the fact that it is difficult to maintain a tight seal in a rotary compressor, since lubricant must be used as a seal and there is a comparatively small area of contact for preventing leakage. When there is an excess pressure differential upon the rotary compressor, the gas will break through the film of lubricant and leak back from the high side to the low side, thereby reducing the efficiency of the compressor and making it impossible to maintain high pressure differentials.

It is an object of our invention to provide a rotary compressor which can operate at relatively high pressure differentials.

It is another object of our invention to provide an extremely simple rotary compressor, having a high efficiency, which will compress gas under relatively high pressure differentials.

It is another object of our invention to provide a rotary compressor of the oscillating eccentric type which is capable of operating under a high pressure differential.

It is a further object of our invention to provide an extremely simple two-stage rotary compressor employing but a single impeller.

It is another object of our invention to provide a well-balanced two-stage rotary compressor.

Further objects and advantages of the present invention will be apparent from the following description, reference being had to the accompanying drawings, wherein a preferred form of the present invention is clearly shown.

In the drawings:

Fig. 1 is a sectional view of a motor-compressor unit taken along the line 1—1 of Fig. 2 embodying our invention and a partly sectional and partly elevational view of the remaining parts of a refrigerating system for an ice cream cabinet;

Fig. 2 is a sectional view taken along the line 2—2 of Fig. 1; and

Fig. 3 is a sectional view taken along the line 3—3 of Fig. 2.

Briefly, we have shown a refrigerating system for an ice cream cabinet including a motor-compressor unit of the rotary type having a groove, an impeller, a divider block for sealing the groove,

and a means for employing the spaces between the impeller and the two sides of the groove as the first and second stages of multi-stage compression. This is done by causing the gas to be drawn into the chamber surrounding the impeller and pumped into a chamber within the impeller from which the gas is pumped into a chamber between the impeller and the inner edge of the groove and thence into the casing enclosing the motor and compressor.

Referring now to the drawings and particularly Fig. 1, there is shown a refrigerating system including a sealed motor-compressor unit generally designated by the reference character 20 for compressing the refrigerant and for forwarding the compressed refrigerant through conduit 22 to a condenser 24 where the condensed refrigerant is liquefied and collected in a receiver 26. From the receiver 26, the liquid refrigerant is forwarded through a supply conduit 28 to an expansion valve 30 which controls the flow of liquid refrigerant into an evaporating coil 32 located within an insulated ice cream cabinet 34 surrounding the ice cream cans 36. The refrigerant evaporates within the evaporator coil 32 under reduced pressure and is returned to the compressor through the return conduit 38. The operation of the motor-compressor unit is controlled by a snap-acting switch means 40 operated by the thermostat bulb 42 located upon the evaporating coil 32 within the ice cream cabinet.

In order to simplify the motor-compressor unit, we employ a sealed rotary motor-compressor unit. This motor-compressor unit includes 35 an inverted cylindrical casting 44 provided with integral cooling fins on its outer face and having an inner cylindrical chamber 46 provided with an open bottom and a small side inlet chamber 48. The chamber 46 is closed by the bottom 40 casting 50 held in place by a ring 52 which is fastened by screws 54 extending through the adjacent flange portion of the casting 44.

Within the casting 44 is placed a stator 56 of an electric conduction motor which is held 45 in place by a press fit in the casting and by long screws 58 which pass through the laminations of the stator. The rotor 60 is of the usual induction motor type and is fitted onto a drive shaft 62 having its lower end mounted in a bearing 64 which fits into a boss 66 extending upwardly from the bottom casting 50. The upper end of the drive shaft 62 is supported by a bearing 68 fitted into the horizontal wall 70 of the casting 44. This horizontal wall 70 is provided

with an annular groove 72 surrounding the bearing 68.

An oscillatable member 74, commonly called a divider block, fits into arc-shaped notches in the opposite walls of the groove 72 in order to provide a seal extending across the groove. An impeller 76 is provided with a rather large arc-shaped projection 78 extending nearly 360° which fits into the groove 72 and is adapted to make sealing contact with the bottom of the groove. This projection is notched so as to receive the divider block 74 upon its opposite plane faces. This projection 78 has an outer diameter slightly less than the outer diameter of the groove 72, while its inner diameter is slightly greater than the inner diameter of the groove 72.

The impeller 76 is provided with an outer flange 80 which makes sealing contact with a machined face 82 upon the upper face of the casting 44. The impeller 76 also has an inner flange 84 adapted to make sealing contact with the machined top surface of the casting 44 upon the inside of the groove 72. The flange 84 also receives the outer race of a ball bearing 88 having its inner race fitted onto an eccentric projection 90 of the drive shaft 62. This eccentric projection 90 is provided with a threaded extension 92 which is concentric with the drive shaft 62. A balance weight 94 is fastened onto the end of the eccentric projection 90 by a nut 96 which is threaded onto the threaded extension 92 in order to hold the balance weight 94 in place. The center of mass of the balance weight 94 is diametrically opposite the center of mass of the eccentric projection 90 and the impeller 76. In this way, the eccentric mass of the balance weight will balance the eccentric mass of the impeller and the eccentric. This portion of the compressor is enclosed by a top casting 102 which is fastened onto the top of the casting 44 by screws 104.

The refrigerant enters the motor-compressor unit through a plug 106 which closes the bottom of the chamber 48. This plug is provided with a check valve 108 held in place by a cage 110. The gas flows through chamber 48 to a horizontal passage 112 which extends to the inside of the groove 72 directly adjacent the divider block 74. Upon the opposite side of the divider block, the impeller is provided with a horizontal passage 114 which extends into a groove 118 provided in the bottom of the projection 78 of the impeller. A check valve 120 is provided at the outlet of the passage 114 to prevent gas from flowing from the groove 118 back into passage 114. The passage 122 extends from the groove 118 to the inner face of the projection 78 of the impeller 76. The impeller 76 is also provided with an outlet passage 124 provided with a check valve 126 which permits the flow of gas out of the inner chamber into the chamber formed beneath the top casting 102 from which the gas passes through the tube 126 into the motor-generator. A tapped hole 128 in the side of the casting 44 connects the motor chamber with the supply conduit 22.

When the motor operates, the impeller is oscillated by its eccentric so that it begins its movement in contact with the outer wall of the groove adjacent the outlet of the passage 112, and this point of contact gradually moves around the outer wall of the groove pushing gas ahead of this point of contact until the point of contact reaches the other side of the divider block 74 where the passage 114 is located. As this point

of contact moves around the outer wall of the groove 72, the gas is pushed ahead of it between the outer wall of the groove and the outer wall of the impeller through the passage 114 past the check valve 120 into the groove 118. The groove 118 serves as the intermediate pressure chamber and contains the gas which has been compressed in its first stage between the outer wall of the impeller and the outer wall of the groove. The gas then passes through the passage 122 into the space between the inner wall of the groove and the inner wall of the impeller.

The gas is first admitted into this inner chamber; and, after the point of contact between the outer walls of the impeller and the groove has moved to a point opposite the divider block, the passage 122 is closed and the second stage compression is begun in the inner chamber between the inner walls of the groove and the impeller. This second stage compression is completed in slightly less than 360 degrees of rotation, and throughout the latter portion of this rotation the gas is forced out through the passage 124 past the check valve 126. It should be noted that the second stage compression is completed when the first stage compression is near the middle of its stroke and the higher fluid pressure upon the smaller inner wall of the impeller is approximately balanced by the lower fluid pressure upon the larger outer wall.

The capacity of the two chambers may be proportioned by the relative diameter of the two chambers, which is governed by the thickness of the projection 78 of the impeller 76. Preferably, the capacities are so adjusted that the pressure within the intermediate chamber, that is in the groove 118, is substantially a mid point between the suction and discharge pressures.

While the form of embodiment of the invention as herein disclosed, constitutes a preferred form, it is to be understood that other forms might be adopted, all coming within the scope of the claims which follow.

What is claimed is as follows:

1. A rotary compressor comprising a stationary member and an impeller member, said stationary member being provided with an annular recess, said impeller member being located within said recess dividing said recess into inner and outer pumping chambers, means for oscillating said impeller member to move gas around the recess upon the inside and the outside of the impeller member, means for providing a seal extending across said recess in sealing engagement with said impeller member, the portion of said impeller member within said recess being provided with a cavity of large volume, said impeller being provided with a passage forming the outlet of one of said pumping chambers and leading directly into said cavity, said impeller being provided with another passage forming the outlet of said cavity and leading directly into the inlet portion of the other pumping chamber.

2. A rotary compressor comprising a stationary member and an impeller member, said stationary member being provided with an annular groove and flat surfaces extending along the edges of the groove, said impeller member being provided with a portion extending to and making sealing engagement with the bottom of the groove dividing said groove into inner and outer pumping chambers, said extending portion having a thickness less than the width of the groove, said impeller having another portion making sealing engagement with said flat surfaces, means for

providing a seal extending across the groove into sealing engagement with said impeller, said extending portion being provided with a large cavity having a large mouth closed by the bottom 5 of said groove, said impeller member being provided with a passage connecting the outlet portion of one of said pumping chambers and said cavity, said impeller member being also provided

with a passage connecting said cavity and the inlet of the other pumping chamber, and means for oscillating the impeller to pump fluid from one chamber into the cavity and thence into the other chamber.
